UNITED STATES PATENT OFFICE.

WILLIAM H. SWINDELL AND LEWIS PHILLIPS, OF WALDO, FLORIDA.

RAIL JOINT.

Application filed October 26, 1922. Serial No. 596,995.

To all whom it may concern:

Be it known that we, WILLIAM H. SWINDELL and LEWIS PHILLIPS, citizens of the United States, residing at Waldo, in the county of Alachua and State of Florida, have invented certain new and useful Improvements in Rail Joints, of which the following is a specification.

This invention relates to rail joints and has for its object to provide a joint of such class, with means in a manner as herein-after set forth, for connecting a pair of opposed track rail sections together to provide for their separation on contraction due to climatic conditions, and further to provide a joint so set up with respect to the track rail sections whereby the cost of upkeep with respect to the track is reduced, as well as reducing to a minimum the jarring of the rolling stock at the joints whereby the life of the latter is increased.

Further objects of the invention are to provide a rail joint which is simple in its construction and arrangement, providing for the contraction and expansion of the track rail sections due to climatic conditions, strong, durable, efficient and convenient in its use, readily assembled with respect to the track rail sections and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a side elevation broken away, of a pair of opposed track rail sections, showing the adaptation thereto of a rail joint in accordance with this invention.

Figure 2 is a section on line 2-2, Figure 1.

Figure 3 is a perspective view of the fish plates or angle bars with the track rail sections removed,

Figure 4 is a perspective view of the chair plate.

Referring to the drawings in detail, 1

and 2 denote a pair of opposed track rail sections and each includes a head 3, a web 4 and a base 5. A pair of transverse ties are indicated at 6, 7.

Mounted upon the ties 6, 7, as well as 60 bridging the space formed therebetween, is a rail chair consisting of a rectangular plate 8, formed centrally with a longitudinally extending seat 9, in which is mounted the base 5, of the track rail sections 1, 2. 65 Each end of the plate 8 is formed with a depending flange 10, which abuts against the outer side of each of the ties 6, 7. At each corner of the plate 8, an opening 11, is provided through which extends a spike 70 12, which engages in a tie. The plate 8, in proximity to the seat 9 and between the center and each end of the plate 8, as well as being positioned inwardly with respect to the openings 11, are openings 12, for the 75 passage of the spikes 13, which also engage in the ties.

Positioned on opposite sides of the track rail sections 1, 2, is a pair of oppositely disposed fish plates or angle bars and each is 80 formed of a rectangular body portion 14, having a bevelled top edge 15, and a plurality of openings 16, for the passage of the bolts 17. Openings 18, are provided in the webs 4, in the track rail sections 1, 2, which 85 register with the openings 16, in the body portion 14. Nuts 19' are mounted on the threaded ends of the bolts 17. The body portion 14 is illustrated as provided with four openings 16, two arranged for the passage of the bolts 17 in connection with each track rail section, but it is to be stated that the body portion 14, can be provided with any suitable number and arrangement of bolt openings 16, corresponding to the 90 number of openings in the webs 4.

Formed integral with the bottom of the body portion 14, as well as projecting outwardly therefrom, is a flange 19, having a pair of spaced extensions 20, which are offset with respect to the flange 19 thereby providing shoulders 21. The flange 19 is of the same length as the body portion 14, and the extensions 20 are flush with the end edges of the flange 19, but the inner ends of the 100 flanges 20 are spaced from each other. Each of the extensions 20 is formed with a slot 22. When the angle bars are set up each flange 19, is seated on the bases 5 of the sections 1, 2, the shoulders 21 abut against 105 110

the edges of the said bases and the flanges 20 are seated upon the plate 8.

The flange 19, between the inner ends of the extensions 20, is formed with a depending lug 23, which when the fish plate or angle bar is secured in position, with respect to the track rail 1, 2, extends down through a longitudinal slot 24, formed in the plate 8. A slot 24 is arranged at each 10 side of seat 9 centrally of the plate 8, and each of the slots 24 is of greater length than the width of the lug 23 to provide for the shifting of the angle bars during contraction and expansion of the track rail sections 15 1, 2.

The spikes 13, extend down through the slots 22, in the extensions 20, and also through the openings 12 in the plate 8, and the heads of the spikes 13 overlap the flanges 20 19. The slots 24 are provided to permit of the shifting of the track rail sections, with the fish plates or angle bars, during the contraction and expansion of the track rail sections and the slots 22, also permit of this 25 shifting.

From the foregoing description taken in connection with the accompanying drawings a rail joint is set up possessing the advantages as herein referred to and although the 30 preferred embodiment of the invention is as illustrated, it is to be understood however, that changes in the details of construction can be had without departing from the spirit of the invention as claimed.

35 What we claim is:—

1. A rail joint comprising a chair plate, a pair of oppositely disposed angle bars formed with slotted extensions and depending lugs, said extensions seated on said plate, and said lugs extending through the plate, certain 40 of said securing elements extending through

said slotted extensions and further extended on said angle bars.

2. A rail joint comprising a flanged chair 45 plate adapted to overlap a pair of ties and formed with a rail seat and a pair of slots, a pair of angle bars adapted to be secured against the opposite sides of a pair of track-rail sections and formed with slotted extensions 50 mounted on said plate, securing elements extending through said plate, certain of said securing elements extended through said slotted extensions and further overlapping said angle bars, and depending lugs 55 carried by the angle bars between said extensions and projecting through the slots of the plate, said lugs of less width than the length of the slot.

3. A rail joint comprising a chair plate, 60 angle bars formed with slotted extensions mounted on said plate, means for connecting the angle bars to a pair of track rail sections, securing means for said plate extended through said slotted extensions, and 65 lugs depending from the angle bars and passing through said plate.

4. A rail joint comprising a pair of angle bars adapted to be secured to a pair of track rail sections and each provided with a pair 70 of slotted extensions and a depending lug positioned between the extensions, a chair plate formed with a pair of opposed slots, said lugs depending through said slots, said extensions seated on said chair plate, and 75 securing elements for said plate, certain of said securing elements extended through the slotted extensions and overlapping said angle bars.

In testimony whereof, we affix our signatures hereto.

WILLIAM H. SWINDELL.
LEWIS PHILLIPS.
